CIRCULATION CONTROL FOR BOILERS

Robert M. Nalven, Kew Gardens, N. Y., assignor,
by mesne assignments, to Combustion Engi-
neering-Superheater, Inc., New York, N. Y., a
corporation of Delaware

Application March 1, 1944, Serial No. 524,535

8 Claims. (Cl. 122—411)

1

This invention relates to steam generators and particularly to those having forced water circulation.

In boilers where water is circulated from a steam and water separating drum through steam generating tubes and back to the drum by means of a pump, there is a possibility of loss of service of the unit due to failure of the pump and to meet this situation it has been customary to provide duplicate pumps. Since the weight of water is about five or more times the weight of steam generated by the boiler at full load the circulation pumps are relatively large and each additional pump increases the space occupied by the boiler unit and also requires additional piping and valves. The necessity of utilizing space in this way and the complication of pipe work is particularly objectionable in marine boiler installations where both weight and space are critical and simplicity a consideration of design. Thus, it would be desirable to omit all but one of the circulation pumps were it not for the handicap of relying upon a single pump for circulation of the boiler water.

It is an object of this invention to overcome the above mentioned disadvantages by providing a novel arrangement for insuring circulation of the boiler water through the steam generation tubes if the circulation pump fails.

In the drawings:

Figure 1 is a diagrammatic elevational view of a steam boiler embodying the invention.

Figures 2 and 3 are diagrammatic illustrations of diaphragm operated valves utilized in the water circulating system of Figure 1; and

Figure 4 is a fragmentary view showing an alternative arrangement.

The steam boiler comprises a steam and water separating drum 10 connected to the steam and water tubes and by means of downcomer pipe 11 to a water circulating pump 12. Steam evaporation tubes 14, of which one appears in Fig. 1, are connected at one end to a distribution header 15 supplied by pump 12 and at their other ends discharge into the steam and water drum 10. The pump 12 is connected to distribution header 15 by means of a pipe 16 having a check valve 17 interposed therein. Boiler water is circulated by means of pump 12 through the steam evaporation tubes 14 at rates equal to several times the weight of steam evaporated.

The evaporation tubes 14 are housed within walls 18 forming a furnace 19 at the top of which the tubes may pass back and forth across the furnace outlet 21 to form a convection bank. With-

2

in the furnace oftake 3 are located a superheater 2 and an economizer comprising a multiplicity of tubes 25 arranged in parallel alignment in directions perpendicular to the plane of the drawing and receiving water from a boiler feed pump 26. The water from all economizer tubes passes into a header 28 and via pipes 30, 31 with interposed valve 32 to the steam and water drum 10. From pipe 30 a branch connection 33 with valve 34 leads to water distribution header 15. Water from economizer header 28 may thus be optionally directed via pipe 30, valve 32 and pipe 31 to the steam and water drum 10 or via valve 34 and pipe 33 to distribution header 15. A check valve 35 may be mounted in pipe 33 as shown in Fig. 4 and valve 34 omitted.

Valves 32 and 34 may be hand controlled but are preferably operated automatically by motors 36 and 37 responsive to the flow of water in the circulation pump discharge 16. Said flow of water may be measured by the pressure developed by pump 12 or by the differential pressure between the pump discharge 16 and pressure in the boiler drum. Motors 36 and 37 may then employ diaphragms which act upon the seats of valves 32 and 34 in a known manner as shown in Figs. 2 and 3, to either close or open them against the resistance of springs. The diaphragms of motors 36, 37 are subject to the pressure of the pump discharge on one side through pipes 38 and 39 respectively, on the sides of the diaphragms farthest from the valve discs and steam drum pressures may be transmitted from the pipes 30, 31 into the valve bodies and through the valve stem housings to the side of the diaphragms nearest to the valve.

In operation pump 12 delivers water to header 15 at a pressure sufficiently above boiler pressure to overcome the resistance of the evaporation tube circuits 14 when pumping the required weight of water corresponding to a certain steaming rate of the boiler. The weight of boiler water circulated through the evaporation tubes 14 may be five times or more that of the steam being evaporated in these tubes. When pump 12 fails, valve 32, which is normally open, will be closed, and simultaneously valve 34, which is normally closed, is opened, both of which operations may be effected by hand or automatically because of decrease of pressure on the top of the diaphragms of motors 36 and 37 as described above. Check valve 17 also closes due to loss of circulation pump pressure and feed water from pipe 30 is then delivered through pipe 33 (through check valve 35 if present) to header 15.

If the check valve 35 is installed, valve 34 may be omitted. The pump 12 delivery pressure is substantially above the pressure in the feed water pipe 30 leading from the economizer header 28 to the drum 10 and the check valve 35 (Fig. 4) is normally kept closed due to this pressure difference and is opened by the feed water in line 33.

The feed water supplied to header 15 is equal in weight to the steam being evaporated and hence the pressure drop through the evaporation tube circuits 14 will be relatively small since the resistance through these circuits will vary approximately as the squares of the relative velocities. The pressure required in the pipe 33 above that of the boiler pressure in the drum 10 need then be only sufficient to overcome the reduced pressure drop through the evaporator tube circuits 14, so that this added pressure superimposed upon the boiler feed pump pressure is negligibly small and does not involve any increase in the size of feed pump 26. For example, if the normal discharge pressure of pump 12 is thirty-five pounds above boiler pressure when delivering water at a rate five times the weight of steam evaporated, then increase in discharge pressure for feed pump 26 to deliver water through header 15 into the evaporation tubes 14, at a rate equal to the weight of steam evaporated, will be but about two pounds.

Thus the invention renders it possible to employ a single circulation pump for a forced water circulation boiler in combination with a boiler feed pump of normal size and still maintain a forced circulation of water through the boiler evaporation tubes upon failure of the circulation pump.

What I claim is:

1. In a steam boiler having steam generating tubes connected to discharge into a separating drum to which a circulation pump is connected for supplying said tubes with water taken from said drum, and a second pump connected by piping to supply feed water to said drum; a self-closing valve in said piping; a conduit connecting said piping at a point ahead of the valve therein in the direction of water flow with the admission ends of said tubes; a self-opening valve in said conduit; and means responsive to the normal delivery pressure of said circulation pump for maintaining said self-opening valve closed and said self-closing valve open to prevent feed water from entering said tubes during the delivery of normal pressure by said circulation pump.

2. In a steam boiler having steam generating tubes connected to discharge into a separating drum to which a circulation pump is connected for supplying said tubes with water taken from said drum, a check valve located in the connection between said tubes and pump and arranged to be opened by normal delivery pressure of the latter; and a second pump connected by piping to supply feed water to said drum; a valve in said piping; means responsive to the normal delivery pressure of said circulation pump to maintain said valve open as long as the circulation pump produces said normal pressure; a conduit connecting said piping at a point ahead of the valve therein in the direction of water flow with the admission ends of said tubes; a valve in said conduit; means responsive to the normal delivery pressure of said circulation pump to maintain said last named valve closed as long as the circulation pump produces said normal pressure; and means responsive to decrease of the circulation pump delivery pressure to below said normal value for

5 closing said first mentioned valve and for opening said second mentioned valve so that the feed pump may supply water to said tubes rather than said drum upon outage of said circulation pump.

3. In a steam boiler having steam generating tubes connected to discharge into a separating drum to which a circulation pump is connected for supplying said tubes with water taken from said drum, a check valve in the connection between said tubes and pump arranged to be opened by the pump's normal discharge pressure, and a second pump connected by piping to supply feed water to said drum; a valve in said piping; means responsive to the normal discharge pressure of said circulation pump to maintain said valve open as long as the circulation pump produces said normal pressure and means to close the valve when the pump discharge pressure drops substantially below normal; a conduit connecting said piping at a point ahead of the valve therein in the direction of water flow with the admission ends of said tubes; and a check valve in said conduit disposed to be closed by the said normal discharge pressure of said circulation pump.

4. In a steam boiler having steam generating tubes connected to discharge into a separating drum to which a circulation pump is connected for supplying said tubes with water taken from said drum, a check valve in the connection between said tubes and pump arranged to be opened by normal delivery pressure of the latter, and a second pump connected by piping to supply feed water to said drum; a valve in said piping; means responsive to the normal delivery pressure of said circulation pump to maintain said valve open as long as the circulation pump produces said normal pressure; a conduit connecting said piping at a point ahead of the valve therein in the direction of water flow with the admission ends of said tubes; a valve in said conduit disposed to be normally closed by the delivery pressure of said circulation pump; and means responsive to decrease of the circulation pump delivery pressure to below said normal value for closing said first mentioned valve so that the feed pump may supply water to said tubes rather than said drum upon outage of said circulation pump.

5. In a steam boiler having steam generating tubes connected to discharge into a separating drum to which a circulation pump is connected for supplying said tubes through a pipe with water taken from said drum, and a second pump connected by piping to supply feed water to said drum; a valve in said piping; means responsive to the normal delivery pressure of said circulation pump to maintain said valve open as long as the circulation pump produces said normal pressure; a conduit connecting said piping at a point ahead of the valve therein in the direction of water flow with the admission ends of said tubes; a check valve in said conduit disposed to be closed by said normal circulation pump delivery pressure; a check valve in said pipe disposed to be opened by said normal circulation pump delivery pressure; and means responsive to decrease of the delivery pressure of said circulation pump to below said normal value for closing said first mentioned valve so that the feed water pump may supply water to said tubes rather than said drum upon outage of said circulation pump.

6. In a steam boiler having a water separator with steam generating tubes connected thereto, a circulation pump, a pipe connecting the pump into the boiler circulation in series with the generating tubes, a check valve in said pipe arranged

to be opened by the normal delivery pressure of said circulation pump, and a boiler feed pump; piping connecting said feed pump to the steam generating tubes beyond said check valve with respect to the direction of circulation; a branch pipe connecting said piping with the separator; a self-closing valve in the branch pipe; a check valve in the piping connecting the feed pump to the steam generator tubes preventing flow from said circulation pump through said piping; and motor means responsive to the production of normal discharge pressure by the circulation pump for maintaining open the said self-closing valve in the branch pipe whereby then to permit flow from said feed pump into the separator.

7. In a steam boiler having a water separator with steam generating tubes connected thereto, a circulation pump, a pipe connecting the pump into the boiler circulation in series with the generating tubes, a check valve in said pipe arranged to be opened by the normal delivery pressure of said circulation pump, and a boiler feed pump; piping connecting said feed pump to the steam generating tubes beyond said check valve with respect to the direction of circulation; a branch pipe connecting said piping with the separator; a valve in the branch pipe connecting the feed pump to the separator; means responsive to the normal delivery pressure of said circulation pump to maintain said second named valve open as long as the circulation pump produces said normal pressure; a valve in the aforesaid piping connecting the feed pump to the steam generating tubes, said third named valve being located beyond the connection of said branch pipe with the piping in the direction of water flow from the feed pump therethrough; means responsive to the normal delivery pressure of said circulation pump to maintain said third named valve closed as long

40

as the circulation pump produces said normal pressure; and means responsive to the difference between the circulation pump discharge and separator pressures for respectively closing and opening the second and third mentioned valves in the lines connecting the feed pump to said separator and to said tubes upon outage of said circulation pump.

8. In a steam boiler having steam generating tubes connected to discharge into a separating drum to which a circulation pump is connected for supplying said tubes through a pipe with water taken from said drum, and a second pump connected by piping to supply feed water to said drum; a self-closing valve in said piping; means responsive to the production of normal discharge pressure by the circulation pump for maintaining said valve open; a conduit connecting said piping at a point ahead of the valve therein in the direction of water flow with the admission ends of said tubes; a valve in said conduit arranged to open upon decrease of said circulation pump delivery pressure below normal; and a check valve in said pipe disposed to be opened by said normal pump discharge pressure.
